UNITED STATES PATENT OFFICE.

JOHN HEATON AND GEORGE HENRY HOLDEN, OF MANCHESTER, ENGLAND.

APPARATUS FOR THE MANUFACTURE OF STEEL OR IRON.

SPECIFICATION forming part of Letters Patent No. 501,139, dated July 11, 1893.

Application filed March 1, 1892. Serial No. 423,424. (No model.) Patented in England May 7, 1890, No. 7,070; in France March 1, 1891, No. 94,019; in Belgium March 5, 1891, No. 211,904; in Germany March 5, 1891, No. 10,873; in Luxembourg March 6, 1891, No. 1,416, and in Canada September 17, 1891, No. 37,421.

To all whom it may concern:

Be it known that we, JOHN HEATON and GEORGE HENRY HOLDEN, subjects of the Queen of Great Britain and Ireland, residing at Manchester, in the county of Lancaster, England, have invented Improvements in Apparatus for the Manufacture of Steel or Iron, (said invention having been patented in the following foreign countries: Great Britain, No. 7,070, dated May 7, 1890; France, No. 94,019, dated March 1, 1891; Belgium, No. 211,904, dated March 5, 1891; Germany, No. 10,873, dated March 5, 1891; Canada, No. 37,421, dated September 17, 1891, and Luxembourg, No. 1,416, dated March 6, 1891,) of which the following is a specification.

In the specifications of British Letters Patent granted to one of us, viz., the said John Heaton, dated respectively March 17, 1866, No. 798, and May 3, 1867, No. 1,295, there is described the manufacture of steel or ingot iron from cast or pig iron by subjecting such iron when in a molten state to the action of nitrate of soda, nitrate of potash, chlorate of soda or chlorate of potash. Now the present invention has reference to improvements in the machinery or apparatus employed in such manufacture as I will now proceed to describe by reference to the accompanying drawings in

30 which—

Figure 1 is a side view partly in section of apparatus constructed according to this invention. Fig. 2 is a vertical section in a plane at right angles to Fig. 1 showing a part of such apparatus. Fig. 3 is a vertical section through the complete apparatus.

40 *a* is a cupola furnace in which the cast or pig iron to be converted into steel or ingot iron according to the process referred to, is melted.

b is a measuring vessel into which a desired quantity of molten metal is run from the cupola furnace *a* by means of the spout *c*. This measuring vessel is formed to hold a certain quantity of molten metal, and is provided with a lid *b'* which is closed after the molten metal has been run into the vessel *b*.

d is a Heaton converter of the well-known

type comprising a vertical cylindrical converting chamber having a removable bottom and surmounted by a shaft or flue, these parts being lined with refractory material. The interior of the measuring vessel communicates with the interior of this converter *d* by means of a lateral passage *b*² capable of being at times closed by means of one or more suitable plugs or valves *b*³, that serve or serve to allow the molten metal to flow from the measuring vessel into the converter and also to prevent sparks or flame from passing from the converter into the measuring vessel while the converting operation is in progress. At the commencement of each "shift" or converting operation, the lower portion *d'* of the body of the converter *d* is or may be heated by any suitable means, preferably by a suitable gas arrangement, to a low red heat in order to prevent undue lowering of the temperature of the molten metal during the converting operation so that the required uniformity of production may be secured.

e is a vessel or chamber, hereinafter called the lower portion of the converter, employed to contain the charge of nitrate or chlorate of soda or potash (hereinafter referred to as nitrate of soda) employed in carrying out the converting process. It is provided with trunnions *e'* by which it is supported upon a truck *f* (Figs. 5 and 6) provided with wheels *f'* capable of running upon the rails *g*. In order to admit of its being readily and conveniently placed in position beneath the converter *d*, the truck *f* is run beneath the converter *d* and onto the table *h* of a hydraulic ram *h'*, or other suitable means such for instance as screws or levers, by which the truck *f* can be raised until the lower portion *e* of the converter carried thereby, comes in contact with and into position beneath the converter *d* to which it is firmly secured by suitable appliances such as clamps *d*² as indicated in dotted lines in Fig. 1, so that should the hydraulic ram *h'* or other means employed, from any cause cease to support the lower portion *e* of the converter, such lower portion of the con-

verter will not become separated from the upper part of the converter. The trunnions *e*' admit of the lower portion *e* of the converter being readily adapted to the converter *d*.

- 5 In order that the charge of metal obtained by the converting operation may be reheated to such a temperature as to effect the elimination of the gaseous and other impurities which remain incorporated with it at the completion of the converting operation and to render the metal sufficiently fluid to be run into ingots, the lower portion *e* of the converter after being removed from the upper part, is moved by its truck *f* along suitable rails *g* or 10 in any other convenient manner to raising and lowering mechanism such as the table *i* of a hydraulic ram *j* arranged below an opening *k* in the bottom of a reverberatory furnace *l*. This furnace is preferably of the regenerative type as shown, being in communication with a gas producer *m* and provided 15 with a passage *n* for supply of air. With the construction described, when the truck *f* is brought upon the table *i* it is raised by the 20 hydraulic ram *j* in order to force the lower portion *e* of the converter into close contact with the underside of the hearth of the reverberatory furnace and form a tight joint therewith so that its interior is directly below the 25 opening *k* through which flame is then caused to play for a sufficient time upon the contents of the lower portion *e* of the converter for the purpose hereinbefore mentioned. The supply of combustible gas and air is then cut off, 30 and the lower portion *e* of the converter lowered and conveyed to any suitable point where its liquid contents are poured into ingot molds or otherwise disposed of.
- The upper end of the converter *d* may be in 35 direct communication with the external atmosphere. In order however to recover certain useful by-products which would otherwise escape from the upper part of the converter during the converting operation, and 40 be lost, it is advantageous to connect the upper portion of the converter with condensing apparatus as described in the specification of another application for Letters Patent filed by us of even date herewith, Serial No. 423,426.
- 45 This condensing apparatus comprises a condensing tower *O* containing brickwork arranged checker-wise after the manner of the brickwork in a Siemens regenerator, and into the lower end of which the gaseous or vapor- 50 ous products of the converting operation are led for the purpose mentioned. For this purpose the lower end of the condensing tower is connected to the upper part of the converter *d* by a vertical pipe *p*, a horizontal flue *q* and 55 a horizontal branch pipe *r* which is fitted with a valve *s* connected with a chain wheel *t* and by means of which the communication between the converter and the flue *q* can be controlled. The upper part of the converter is 60 also fitted with a valve *u* provided with a chain wheel *v* for controlling the communica- 65

tion between the converter and the external atmosphere. When the valve *s* is closed and the valve *u* is opened, the gaseous or vaporous products of the converting operation will 70 escape from the upper part of the converter into the atmosphere. If the valve *u* be closed and the valve *s* opened, the said products will pass through the branch pipe *r*, flue *q*, and pipe *p* into the bottom of the condensing 75 tower *O*. In some cases, in order to assist the condensing and collecting of the by-products, the condensing tower may be cooled by a shower of water admitted through a pipe *w*, with distributing branches. The water or 80 other liquid or liquids employed in cooling the gaseous or vaporous products, and which will dissolve a great part of the valuable by-products therein, may be run off by a pipe *x* and be afterward treated in any suitable manner 85 for the recovery therefrom of the by-products contained therein.

Steel or ingot iron is manufactured in the above described apparatus as follows:—The pig-iron to be converted into steel or wrought 90 iron is placed in the cupola furnace *a* and melted, and a portion of it is allowed to run along the spout *c* into the measuring vessel *b*. When a sufficient quantity of pig-iron has been run from the cupola furnace into the 95 measuring vessel, the supply of metal from the cupola furnace *a* is shut off. The lower portion *e* of the converter having been charged with the requisite quantity of nitrate of soda, is, by means of the truck *f* and rails *g*, run upon the table *h* which is then raised until the upper edge of the lower portion *e* of the converter is brought into contact with the lower end of the upper part of the converter *d* to which it is secured by means of the 100 clamps *d*². The plug or valve *b*³ is then raised and the molten iron contained in the measuring vessel *b* is allowed to flow into the converter and to come into contact with the nitrate of soda therein by the oxidizing action 105 of which the cast iron is converted into steel or ingot iron according to the quantity of nitrate of soda employed, as described in the 110 said prior British specification No. 1,295 of 1867. When the charge of cast iron in the 115 lower portion *e* of the converter has been converted into steel or ingot iron, the clamps *b*² 120 are removed or loosened, and the table *h* and lower portion *e* of the converter are lowered. The lower portion *e* of the converter is then 125 removed to the reverberatory furnace *l* where its contents are heated as in the manner and for the purpose hereinbefore described after which the purified metal is poured into an ingot mold or otherwise treated. By the apparatus hereinbefore described, the process 130 described in the said prior British specification No. 1,295 of 1867 can be very readily carried out with the employment of comparatively little manual labor.

In the preceding description the term ingot iron is used to denote a metal having a com-

position character and properties similar to those of metal ordinarily designated wrought iron.

What we claim is—

- 5 1. Apparatus for the manufacture of steel and iron by the Heaton process, comprising a cupola, a converter having a lower removable portion, a measuring vessel arranged between and adapted to be placed in communication with said cupola and converter, a carrier whereon the lower removable portion of said converter is mounted, means for raising and lowering said lower portion with its carrier to and from the upper portion of said converter, a reverberatory furnace having an opening through its lower side against which said lower portion of the converter can be held, raising and lowering mechanism below said furnace, and a suitable way arranged 15 between said converter and reverberatory furnace and above said raising and lowering mechanism and whereon said carrier can travel substantially as herein described for the purposes specified.
- 20

2. The improved apparatus or plant for the manufacture of steel and iron by the Heaton process, comprising a cupola, a measuring vessel, a converter having a lower removable portion, a wheeled truck whereon said lower portion is journaled, a hydraulic ram with 25 table *h* arranged below said converter, a reverberatory furnace *l* having an opening *k* through its lower side, a hydraulic ram *j* with table *i*, and rails *g*, extending from said table *h* to said table *i*, these parts being arranged 30 substantially as herein described for the purposes specified.

In testimony whereof we have signed our names to this specification in the presence of two subscribing witnesses.

JOHN HEATON.
